UNITED STATES PATENT OFFICE

94,360

DESIGN FOR AN ADVERTISING NOVELTY IN THE FORM OF A CONTAINER

William D. Rose, Portland, Oreg.

Application July 8, 1933, Serial No. 48,672

Term of patent 3½ years

To all whom it may concern:

Be it known that I, William D. Rose, a citizen of the United States, residing at Portland, in the county of Multnomah and State of Oregon, have invented a new, original, and ornamental Design for an Advertising Novelty in the Form of a Container, of which the following is a specification, reference being had to the accompanying drawing, forming part thereof, and in which:

Figure 1 is a perspective view of the container. Figure 2 is a similar view looking from the bottom of the container and showing the side opposite to that shown in Figure 1.

I claim:

The ornamental design for an advertising novelty in the form of a container, as shown.

WILLIAM D. ROSE.
